UNITED STATES PATENT OFFICE.

EUGENE FONTAINE, OF TOLEDO, OHIO.

RAILWAY-SWITCH.

SPECIFICATION forming part of Letters Patent No. 374,054, dated November 29, 1887.

Application filed April 28, 1887. Serial No. 236,428. (No model.)

To all whom it may concern:

Be it known that I, EUGENE FONTAINE, of Toledo, in the county of Lucas and State of Ohio, have invented new and useful Improvements in Railway-Switches; and I do hereby declare that the following is a full, clear, and exact description thereof, reference being had to the accompanying drawings, which form a part of this specification.

10 This invention relates to new and useful improvements in railway-switches, of which the following is a specification, reference being had to the accompanying drawings, in which—

Figure 1 is a plan of my improved switch. 15 Fig. 2 is an enlarged plan of that portion of said switch which contains the operating switch-lever, and Fig. 3 is an enlarged plan of that portion of said switch which contains the pivotal main rail. Figs. 4 and 5 are sections on lines xx and yy in Fig. 1.

The object of my invention is to construct a switch which forms a continuous rail for the train under all circumstances, the same as at all other points of the track, and thereby prevents entirely the great wear and tear and the damages incident thereto found inseparably connected with the use of fixed frogs and disconnected railway-rails. 25

To this end I have devised the following construction and arrangement of parts.

A A are the fixed rails of the main track. A' A' are movable switch-rails of said track, and A" is a pivot-rail in the main track.

B B are the fixed rails of the siding. 35 The pivot-rail A" has its pivotal point at the intersection of the inner rails of the main line and siding and extends in both directions from its pivot. That portion which connects with the ends of the converging inner rails is made just sufficiently long to give sufficient clearness between such ends to prevent any danger liable to arise from approaching them more closely. The other and longer end extends a sufficient distance to connect directly 40 with either one of the movable rail ends A' A' of the main track, as hereinafter explained.

The pivot of the movable rail-section A" is constructed as follows: Fish-plates D, extending the entire length, or nearly so, of the 45 pivot-rail A", are secured by bolts a to the

sides of the rail to render it very rigid and give it a larger bearing, and at the pivotal point of the rail these fish-plates have enlarged bearings b, and underneath the same and secured thereto by bolts c is a circular turn-table, d, which has a downwardly - projecting pivot, e, and engages into a corresponding aperture in a bed-plate, f, firmly supported underneath. To the under side of the pivot of the turn-table d is secured a plate, g, by means of a suitable bolt, h. The ends of the bed-plate f are bent upwardly to form bearings for the rail and have suitable flanges, i, to form sockets for the converging ends of the fixed rails and half-sockets for the pivot-rail, so as 55 to permit the latter to be turned on its pivot to register either with the siding or with the main track.

The free ends of the rails are supported on a bed-plate, E, which has suitable flanges, k, 60 formed thereon to form sockets to receive the ends of the fixed rails and half-sockets for the ends of the movable rails and the end of the pivot-rail. The bed-plate E is also provided with suitable shoulders, j, which prevent the 65 rails from crowding against each other.

The free end of the pivot-rail is secured to the connecting-rod G by means of a clip, l, which also engages on the edge of the bed-plate E to guide the rail in shifting and prevent its 70 end from springing upward.

The ends of the movable rails A' A' are both secured to the connecting-rod H, which extends parallel with the connecting-rod G to the switch-stand, where one connects to a crank I 75 and the other to a crank J. These two cranks have a common shaft, but are placed upon opposite sides, so that the movement of the switch-lever K, which is secured to said shaft, will draw the connecting-rods in opposite directions, thereby effecting the movements necessary to operate the switch.

The pivot-rail A" may be provided at suitable intervals with bearing-plates L, having the usual flanges to form half-sockets for the 80 rail.

What I claim as my invention is—

1. The combination, with the bed-plate E and pivot-rail A", of the connecting-rod G and the clip l, securing said rod to the said 85

rail and engaging the edge of said bed-plate, substantially as shown and described, and for the purpose specified.

2. The combination of the pivot-rail A", 5 the fish-plates D, embracing the sides of the rail and secured thereto by transverse bolts *a* and having the extended bearings *b*, the turn-table *d*, secured thereto and having the pivot

e, the bed-plate *f*, the plate *g*, and bolt *h*, securing the plate *g* to the under side of the pivot of the turn-table, all combined substantially as described.

EUGENE FONTAINE.
